UNITED STATES PATENT OFFICE.

LEONE ALMAGIA, OF CORNIGLIANO LIGURE, AND ERALDO GUERRESCHI, OF SAMPIERDARENA, ITALY, ASSIGNEES TO SOCIETÀ ANONIMA ITALIANA GIO. ANSALDO & C., OF CORNIGLIANO LIGURE, ITALY.

ELECTRIC FURNACE.

1,336,807.

Specification of Letters Patent. Patented Apr. 13, 1920.

Application filed September 23, 1918. Serial No. 255,377.

To all whom it may concern:

Be it known that we, LEONE ALMAGIA, engineer, subject of the King of Italy, and residing at Cornigliano Ligure, Italy, and 5 ERALDO GUERRESCHI, engineer, subject of the King of Italy, and residing at Sampierdarena, Italy, (the post-office address of both is: % Società Anonima Italiana Gio. Ansaldo & C., Cornigliano Ligure, Italy), have 10 invented certain new and useful Improvements in Electric Furnaces, of which the following is a specification.

This invention has for its object to provide an improved apparatus and an improved electric furnace whereby, with the aid of an electrical machine, there can be obtained the control and the regulation of the distribution of the heat in the various parts of the bath, and an instantaneous automatic regulation of the short-circuit points, thus rendering it possible to supply the furnace with current from any desired distribution cables, even if such cables are employed for lighting a large district. This 25 invention has also for its object to produce steel of superior quality.

One way of performing this invention is illustrated by way of example in the accompanying drawings in which:

30 Figure 1 illustrates an apparatus for a furnace worked with tri-phase current on the Heroult system.

Fig. 2 is a diagram illustrating the voltages A, B, C between the electrodes.

35 Fig. 3 illustrates an apparatus for a furnace worked with tri-phase current on the Girod system.

Fig. 4 is a diagram illustrating the voltages:

$$40 \quad AB = BC = \frac{CA}{\sqrt{3}}$$

being the voltages of each phase of the transformer.

45 Fig. 5 illustrates an apparatus for a furnace worked with tri-phase current on the Ansaldo system.

Fig. 6 is a diagram illustrating the voltages: AB=BC=CA being the voltages between the upper electrodes; ab=bc=ca being the voltages at the lower electrodes; 50 aA=bB=cC being the voltages of each phase of the transformer.

Fig. 7 illustrates a furnace worked with

tri-phase current on the Ansaldi system, 55 with apparatus comprising an auxiliary transformer T².

Fig. 8 is a diagram showing the voltages without the auxiliary transformer T².

Fig. 9 is a diagram showing the voltages 60 with the transformer T²: AB=BC=CA being the voltages between the upper electrodes; ab=bc=ca being the voltages between the lower electrodes; aA=bB=cC being the voltages of each of the phases of 65 the transformer.

The improved furnace, provided with the device shown in Figs. 3 and 7, differs from the electric furnaces at present in use in this that electrodes connected to the beginning 70 and to the end of the several phases of a transformer (or alternator) are arranged upon the surface of the furnace and upon the bottom of the bath, the arrangement being such that the electric current is compelled to pass from an electrode to another at the surface of the bath, and from an electrode at the bottom to another electrode at the bottom, and from an electrode at the surface to an electrode at the bottom through 75 the bath, in such a manner that the bath is traversed by electric currents in all directions and is thus heated not only at the surface as in furnaces at present in use, but is heated both at the surface and in the interior and at the bottom. 80

Moreover, in the apparatus shown in Fig. 7, with the transformer T², a control of the heat is obtained, which heat may be regulated at the will of the operator during 90 the metallurgic process, and therefore during the period of fusion, and in case great variations of current are perceived, the heat can be concentrated upon the bottom of the furnace. 95

During the refining process, it will be advantageous to heat also the slag zone for effecting desulfurization and dephosphorization, and to modify in other respects the heating of the bath according to the requirements 100 of the moment, and with relation to the metal which it is desired to produce, by rendering the heating uniform throughout the mass of the bath during periods of time suggested by experience, thereby producing a metal of superior quality. 105

The transformer T², besides permitting an ideal regulation of the heat, allows also

an automatic and instantaneous regulation of the fluctuations of current.

This regulation contrary to the methods of regulation at present in use, allows of 5 limiting the fluctuations of the current at the moment of their occurrence, so that they are prevented from coming into action.

The foregoing will now be more clearly understood on reference to the accompanying drawings and to the formulae hereinafter given.

In the electrode furnaces illustrated in Figs. 1, 2, 3 and 4, if $-z-$ represents the impedance of the system, and V_s the voltage for the upper electrodes, there frequently occurs a short-circuit current represented by the following formula:

$$i_1 = \frac{V_s}{z} = \frac{C}{z}$$

20 wherein C is a constant.

In the furnace on the Ansaldo system illustrated in Figs. 5 and 6, with the principles of the phases of a transformer at the 25 upper electrodes, we have on the contrary:

$$i_1 = \frac{C}{z+Z}$$

30 where Z is the impedance of the hearth or bottom of the furnace.

From this it results that the short-circuit current is already considerably smaller than in other furnaces, and is still more reduced in the apparatus shown in Figs. 7, 8 35 and 9 comprising a transformer T^2 , the transforming ratio of which is $-a-$, so that we have now:

$$i_1 = \frac{C}{z+Z(l+a)^2}$$

40 By making $-a-$ variable, it is possible to vary the heating at any point whatever

of the bath either near the bottom or near the surface.

In fact, if we limit by

45

W_s the watts used at the surface,
 W_i the watts used at the bottom,

we have:

$$W_s = f[C - Zi_1(l+a)^2]$$

$$W_i = f[Zi_1(l+a)^2]$$

50

where the first function diminishes with the increase of $-a-$ or vice versa, the second being likewise

55

$$W_s - W_i = \text{a constant}$$

whence it follows that the transformer T^2 limits the points of short-circuit within the desired limits and allows of regulating the 60 heat of the furnace.

Having now particularly described and ascertained the nature of our said invention and the manner in which the same is to be performed, we declare that what we 65 claim, is:

A device of the character described including a hearth, a cover therefor electrodes in the hearth and the cover, a transformer conducting wires between the transformer and the electrodes in the cover, other conducting wires between the transformer and the electrodes in the hearth, and a second transformer interposed in the last mentioned conducting wires and in series therewith.

70 In testimony whereof we have hereunto signed our names in the presence of two witnesses.

75 LEONE ALMAGIA.
ERALDO GUERRESCHI.

Witnesses:

CARLO LARAZSI,
AGORTINO SALOMME.
